UNITED STATES PATENT OFFICE

AUBREY O. BRADSHAW, OF BLUEFIELD, WEST VIRGINIA

CARD HOLDER FOR FREIGHT CARS

Application filed August 11, 1930. Serial No. 474,490.

This invention relates to improvements in card holders, and it consists of the constructions, combinations and arrangements herein described and claimed.

An object of the invention is to provide a device for holding cards or tags for all purposes on railroad cars, an especial purpose being to eliminate the need or use of wooden blocks and tacks in conjunction with metallic cars for the purpose of attaching the necessary tags or cards.

Another object of the invention is to provide a card holder which requires only the placing of the card in position and the letting down of an impaling device whereupon the card will be held in place even more firmly than if secured with tacks.

Other objects and advantages will appear in the following specification, reference being had to the accompanying drawings, in which:—

Figure 1 is a perspective view of perhaps the simplest form of the card holder;

Figure 2 is a vertical section taken on the line 2—2 of Figure 1;

Figure 3 is a front elevation of a modified form of the device; and

Figure 4 is a vertical section taken on the line 4—4 of Figure 3.

It is the prevailing practice to attach cards or tags of various kinds and for various purposes to railway rolling stock, especially freight cars. This is a Government regulation, and the requirement respecting closed cars is to provide tags on each of the ends and each of the sides.

In those instances where wooden cars are used, it is a simple matter to tack the cards in place, but the growing use of steel cars makes it necessary to provide wooden blocks at the places indicated and to use tacks for the securing of whatever cards are to be borne by the car.

As already indicated, it is one of the purposes of the invention to eliminate the use of these wooden blocks as well as the use of tacks for securing the tags thereto. Reference is made to the drawings. The card holder 1 comprises a base plate 2 which at its lateral extremities has perforated ears 3

for the purpose of enabling the securing of the holder to the side or end of the car. The manner in which the base plate 1 is secured is immaterial so long as it is permanently mounted on the car. To that end, welding might be resorted to if seen preferable in practice.

Adjacent to the foregoing lateral extremities the base plate has guides 4 which stand out from the face of the plate sufficiently far to receive one or more cards 5 (Fig. 2) therebetween. These guides provide passageways 6 for the edges of the cards, and for the purpose of both assisting the maintenance of the spacing of the free edges of the guides as well as to provide rests for the bottom edges of the card or cards, pins 7 are fitted in place as shown.

An outstanding advantage in the provision of these pins is the freedom of the drainage of moisture from the passageways 6 as well as the dropping out of any cinders that might fall into the passageways. If the bottoms of the passageways 6 were closed, there would be room for an accumulation of moisture which, upon freezing in the winter time, would make it difficult to remove a card when it is desired to do so.

Lugs 8 outstanding from the guides 4 provide bearings for a shaft 9 which carries a plurality of impaling members 10 which generally comprise what is herein known as an impaling device. One of these members includes an arm 11 which terminates in a weight 12 so that said device will always tend to assume the impaling position.

For the latter purpose the weight 12 is either made large enough or is provided with a button 13 on one side to contact the side 14 of the car (Fig. 2) and prevent the arm 11 from assuming a vertical position. In other words, the button 13 holds the arm 11 outwardly past the dead center when moved to the erect position (dotted lines in Fig. 2) so that when the arm 11 is released it automatically falls to the full-line or impaling position.

Each of the impaling members is alike with the exception of the one having the arm 11. Each includes an extension 15 with a

point 16 for the purpose of impaling the card 5 and so holding the latter in place. Perforations 17 are provided in the base plate 2 at the place where the points 16 meet it. The points enter the holes. In order to keep the point from rubbing against the side of the respective hole it is made smaller than the end of the extension 15 so as to leave a shoulder 18.

10 It is the shoulder 18 that will abut the card 5 in the immediate vicinity of the hole 17 (Fig. 2). The point 16 assumes the position within the hole, being entirely out of contact with the sides of the hole, and 15 consequently protected from any wear that would ensue from the motion of the car.

The statement has been made that one or more cards are adapted to be held by the holder 1. Sometimes a half-size card is 20 inserted in the holder. For these purposes the pins 7 are supplemented by a rest 19 which occupies a place under the central impaling member 10 and on the approximate vertical center line of the device. If 25 two cards are inserted the inner edges may be overlapped. Upon letting down the impaling device the central impaling member will secure the central parts of both cards. Should a half-size card be inserted the bottom 30 edges would stand on one of the pins 7 and the rest 19 while the upper edges would be held by the central and side ones of the impaling members 10.

Figure 3 discloses a slight modification 35 of the card holder. The chief difference resides in the provision of a connecting link 20. Otherwise the structure is identical with that already described as is indicated by the corresponding reference characters.

40 It is proposed to make the holder in various sizes. The holder in Fig. 1 is of a small size whereas the holder in Fig. 3 is to be regarded as approximately 20" square for the purpose of holding large warning cards 45 such as are customarily required to be displayed on cars transporting explosives.

With such a large holder it is deemed desirable to duplicate the impaling device. The guides 4 are therefore provided with 50 lugs 21 at the bottom as well as 8 at the top. A duplicate shaft 22 is supported by the lugs 21.

Upon raising the arm 23 of one of the impaling members 10 of the bottom shaft, the 55 impaling members of the top shaft will be raised also by virtue of the connection that the link 20 affords. This link is pivoted to each of the arms 11, 23.

The operation is readily understood. 60 Upon desiring to insert a card, regardless of what the size might be, the operator has only to raise the arm 11 (or 23 in the instance of Figure 3) whereupon the impaling device 10 will be moved clear of the base plate 2. The card is slipped in the

guides 4 which constitute independent holding means, until the bottom edge bears on the pins 7 and rest 19, whereupon the arm 11 is released.

The weight 12 will cause the points 16 to puncture the card and thus secure it in place. The extraction and removal of a card is the work of a very few minutes as compared with the laborious duty of driving tacks through cards into wooden blocks.

75 While the construction and arrangement of the improved card holder is that of a generally preferred form, obviously modifications and changes may be made without departing from the spirit of the invention 80 or the scope of the claims.

I claim:

1. A device of the character described, comprising means to independently support a card, and means movably mounted on the 85 supporting means for securing the card.

2. A device of the character described, comprising an independent card supporting means, a mounting carried by the supporting means, and an impaling device movably carried by the mounting for impaling the card and securing it in position.

90 3. A device of the character described, comprising card-supporting means, a mounting carried by said supporting means, an impaling device for securing the card comprising a shaft supported by the mounting means, an impaling member carried by the shaft, and a weight associated with the shaft tending to always move the impaling member to an impaling position.

95 4. A card holder comprising a base plate, card edge-receiving means on the base plate, a shaft supported in front of said receiving means, an impaling member mounted on the shaft, and means tending to revolve the shaft in one direction and to move the impaling member to an impaling position in respect to the base plate.

100 5. A card holder comprising a base plate, card edge-receiving means, a shaft supported in front of said receiving means, a plurality of impaling members mounted on the shaft, and a weighted arm extending from one of the impaling members tending to revolve the shaft in one direction and to move all of the impaling members to an impaling position in reference to the base plate.

105 6. A card holder comprising a base plate having a perforation, card edge-receiving means, a shaft supported by said means, and an impaling member mounted on the shaft including an extension terminating in a shoulder abuttable with the face of a card 110 adjacent to the perforation and having a point to puncture the card and enter the perforation, and means for moving the shaft to an impaling position of said member.

115 7. A card holder comprising a base plate 120

having perforations near the upper and lower edges, card edge-receiving means at the sides of said plate, shafts journaled on said receiving means adjacent to the upper and lower edges of the plate, impaling means mounted on each of the shafts including points entering the perforations to secure a card, weighted means on each shaft tending to move the shaft to an impaling position, and means connecting the weighted means so that a lifting motion of one will be communicated to the other.
